(Cl. D90—20)

To all whom it may concern:

Be it known that I, Arthur H. Nellen, a citizen of the United States and a resident of Philadelphia, county of Philadelphia, State of Pennsylvania, have invented a new, original, and ornamental Design for a Vehicle Tire, of which the following is a specification, reference being had to the accompanying drawings forming a part thereof, wherein:

Fig. 1 is a perspective view of a vehicle tire showing my new design; and

Fig. 2 is a fragmentary top plan view thereof.

I claim:

The ornamental design for a vehicle tire, as shown.

ARTHUR H. NELLEN.
